ART OF CRACKING HYDROCARBONS

Application filed September 29, 1927. Serial No. 222,912.

This invention relates to improvements in the cracking of heavier and higher boiling hydrocarbon oils, such as gas oil, for the production therefrom of lighter and lower boiling hydrocarbon oils, such as gasoline, particularly by distillation under pressure.

The vapor mixture from pressure distillation cracking operations usually includes, in addition to vapors of the desired lighter and lower boiling oils, vapors of heavier and higher boiling oils not suitable as components of the desired product but which are with advantage again subjected to the cracking operation, and for this reason the vapor mixture from the cracking operation proper is usually subjected to a refluxing operation for separation of such heavier and higher boiling components again to be subjected to the cracking operation. As commonly carried out, this refluxing operation usually involves entrainment, dissolved or entrapped, in the reflux condensate of lighter and lower boiling components of the vapor mixture suitable as components of the desired product. The return of such lighter and lower boiling components to the cracking operation proper in turn involves not only an objectionable tendency toward overcracking of such components with consequent loss but also an objectionable tendency toward increase in the formation of "carbon". Where the refluxing operation is effected or controlled by direct introduction of more or less of the raw oil to be supplied to the cracking operation, this tendency toward entrainment is usually increased.

The reflux condensate from such refluxing operations is usually relatively refractory with respect to the cracking conditions prevailing in the operation, and for this reason is with advantage subjected to more severe cracking conditions. One advantageous method of handling this refractory stock, in externally heated apparatus, is to pass it in heat exchange with the heating gases for

supplying heat to the operation while these heating gases are at highest temperature, and before they pass in heat exchange with the less refractory stock undergoing treatment, for example as described in my application filed September 24, 1923, Serial No. 664,502. The heating surfaces over which the less refractory, or more easily cracked, stock circulates may thus be protected against overheating while at the same time the more refractory stock is subjected to advantageous cracking conditions. Circulation of the more refractory stock over the heating surfaces first contacting with the heating gases also affords an important measure of protection to these heating surfaces subjected to highest temperature.

However, where the reflux condensate or the oil mixture from the refluxing operation includes entrained lighter and lower boiling components suitable as components of the desired product, any tendency toward overcracking of such components or toward increase in the formation of "carbon" is accentuated by subjecting such reflux condensate or oil mixture to more severe cracking conditions. This invention provides an improved operation in which such reflux condensate or oil mixture is subjected to more severe cracking conditions but in which any such tendency is minimized by stripping such lighter and lower boiling components from the reflux condensate or oil mixture before it is again subjected to cracking conditions in the operation.

According to the present invention, a body of oil is heated to a cracking temperature by circulating the oil over heating surfaces externally in contact with heating gases, vapors including vapors of the cracked product are taken off from this body of oil under pressure, these vapors are subjected to a refluxing operation from which the vapors remaining uncondensed including vapors of the desired distillate product are discharged,

after discharge from the refluxing operation any components of the reflux condensate suitable as components of the desired product are vaporized and separated therefrom, the 5 remaining reflux condensate stripped of such components is circulated over separate heating surfaces externally in contact with heating gases, and the heating gases for supplying heat to the operation are passed first over 10 the last mentioned separate heating surfaces and then over the first mentioned heating surfaces. The reflux condensate is thus subjected to more severe cracking conditions but only after separation of lighter 15 and lower boiling components the return of which might tend to involve overcracking or excessive formation of "carbon".

After circulation over the heating surfaces with which the heating gases first contact, the resulting hot oil products may with 20 advantage be discharged into the body of oil from which vapors are taken off to the refluxing operation. The refluxing operation may be effected or controlled by indirect heat 25 exchange with some suitable medium or the refluxing operation may be effected or controlled by the direct introduction into the vapors in the refluxing operation of raw oil to be supplied to the cracking operation. In 30 such operation, where the raw oil or part of the raw oil is introduced into the refluxing operation, the raw oil remaining unvaporized is discharged in admixture with the reflux condensate and passes therewith successively through the stripping operation for 35 separation of lighter and lower boiling components and then over the separate heating surfaces with which the heating gases first contact. The raw oil component of such oil 40 mixtures is free from tarry or pitchy constituents produced in the cracking operation and therefore assists in protecting the separate heating surfaces. The refluxing operation may also be effected or controlled by the direct introduction of a part of the distillate product or of a fraction of corresponding 45 character. The vaporization of lighter and lower boiling components from the reflux condensate or oil mixture discharged from the refluxing operation may be effected by reheating the reflux condensate or oil mixture or by reducing the pressure thereon and separating the components consequently vaporized or by both reheating and reducing the 50 pressure on the reflux condensate or oil mixture.

The invention will be further described in connection with the accompanying drawings 55 which illustrate, diagrammatically and conventionally, apparatus adapted for carrying out the invention, but it is intended and will be understood that this further and more detailed description and illustration are by way 60 of exemplification and that the invention is

not limited thereto. In the accompanying drawings:

Fig. 1 represents, in elevation and partly in section and with parts broken away, a pressure still system adapted for carrying out one embodiment of the invention, and 70

Fig. 2 represents, in elevation and partly in section and with parts broken away, a pressure still system adapted for carrying out another embodiment of the invention. 75

Referring to the drawings, particularly Fig. 1, the pressure still illustrated comprises a bulk supply drum 1, a battery of heating tubes 2 arranged in the heating flue of a furnace 3, and circulating connections 4, 5 and 6 including circulating pump 7 for circulating oil from the bulk supply drum upwardly through the heating tubes 2 and back to the bulk supply drum, and an auxiliary bank of heating tubes 8 arranged in the furnace 3 in the path of the heating gases from the firebox of the furnace in advance of the heating tubes 2. Arranged above the bulk supply drum 1 is a reflux tower 9. This tower may be of ordinary open baffle construction as illustrated. Vapors escape from the bulk supply drum 1 through connection 10 into the lower end of the reflux tower 9 and vapors remaining uncondensed escape from the upper end of this tower through connection 11 to condenser 12. This condenser discharges into receiver 13 from which the distillate product is discharged through connection 14 and uncondensed vapors and gases through connection 15. The pressure in the system may be maintained and regulated by means of valve 16 or by means of suitable valves arranged beyond the condenser or receiver. Connection 17 is provided for the direct introduction of raw oil into the upper end of the reflux tower 9 and connection 20 for the introduction of raw oil into the circulating still charge through the bearings of the circulating pump 7. Connection 21 is provided for initially charging the still and for pumping out the still at the end of a run. Connection 22 is provided for discharging pitch laden oil or tar during operation. Reflux condensate or admixed reflux condensate and raw oil is discharged from the lower end of the reflux tower 9 through connection 23 to the separating drum 24. From this separating drum oil is circulated through connection 25 by means of pump 26 to and through the bank of heating tubes 27 and thence back to the separating drum 24 through connection 28. Vapors from the separating drum escape through connection 29, for example into the reflux tower 9 as in the apparatus illustrated in Fig. 1. The oil remaining unvaporized in separating drum 24 flows to pump 30 through connection 31 and by this pump is forced through the heating tubes 8 and thence through connection 32 and the circulating

connections 6 into the bulk supply drum 1. Any excess of reflux condensate or oil mixture collecting in the lower end of the reflux tower 9 may be returned to the bulk supply drum 1 through overflow connection 33 or 5 may be discharged from the separating drum through connection 34. Additional raw oil to be circulated through the heating tubes 8 may also be supplied to the separating 10 drum 24 through connection 34. Connection 35 is provided for circulating oil from the body in the bulk supply drum 1 through the heating tubes 8 while the still is being brought 15 to operating conditions of temperature and pressure.

One convenient means for controlling the heating of the oil passing through the heating tubes 27 is illustrated in the drawings. A part of the escaping heating gases is 20 circulated through the blower 36 to pass again over the heating tubes 8 and the heating tubes 2 in admixture with fresh hot products of combustion from the fire-box of the heating furnace, as described in Letters Patent No. 1,574,546 and No. 1,574,547 granted February 23, 1926, to the Sinclair Refining Company on applications of John E. Bell, and the temperature increment imparted to 25 the oil passing through the heating tubes 27 is controlled by withdrawing the heating gases so recirculated either all from in front of the heating tubes 27 or all from behind these heating tubes or partly, in any required degree of division, from in front or partly 30 from behind these heating tubes through the adjustable dampers 18 and 19. The reflux condensate or oil mixture from the reflux tower 9 may be reheated in an independently fired furnace as well as in the main furnace, 35 as illustrated, for the separation of lighter and lower boiling components.

To minimize heat loss, the bulk supply drum 1, the circulating connections 4, 5 and 6, the reflux tower 9, the separating drum 24, the 40 vapor connection 10 and the return connection 23, as well as other exposed parts of the pressure still system, are advantageously lagged or thermally insulated.

The following example of an operation to 45 produce gasoline from gas oil will serve to illustrate the operation of apparatus of the type illustrated in Fig. 1 in carrying out the invention. The pressure still is initially charged with about 8,000 gallons of gas oil and brought to cracking conditions of temperature and pressure in the usual way, circulation from the bulk supply drum being maintained through heating tubes 8 and back to the bulk supply drum as well as through 50 heating tubes 2 and back to the bulk supply drum during this period. When the still is brought to a pressure of say 150 pounds to 200 pounds per square inch, the introduction of raw oil through connection 17 is started 55 and as sufficient oil mixture accumulates in

the separating drum 24 circulation through connection 35 is gradually cut off, finally completely cut off, and this oil mixture is circulated through the heating tubes 8 thence into the bulk supply drum by means of pump 30. During the initial period of operation, a small amount of gas oil is kept in circulation from the separating drum 24 through the heating tubes 27 and back to the separating drum, this amount being maintained by the addition of raw oil through connection 34 if necessary, and as the oil mixture from the reflux tower accumulates this initial supply of oil to protect the heating tubes 27 during the initial period of operation is gradually displaced by the oil mixture from the reflux tower. During the initial period of operation a small flow of raw oil is maintained through connection 20 to cool and lubricate the bearings of the circulating pump; after operating 70 conditions of temperature and pressure are reached any additional raw oil required to maintain the still charge over that introduced through the reflux tower may also be supplied through this connection. As the 75 introduction of raw oil through the reflux tower is begun, or shortly before or shortly thereafter as required if the still charge is above or below normal, the discharge of pitch laden oil or tar through connection 22 is begun. When this point in the operation 80 is reached, for example, raw oil may be supplied at a rate in the neighborhood of 2,500 gallons per hour, distillate taken off at a rate in the neighborhood of 1,000 gallons per hour and tar discharged at a rate in the 85 neighborhood of 1,500 gallons per hour.

When this point in the operation is reached, oil is in circulation from the bulk supply drum 1 through the heating tubes 2 and back to the bulk supply drum, vapors including vapors of the cracked products discharged both from the heating tubes 2 and the heating tubes 8 are escaping from the bulk supply drum 1 to the reflux tower 9, vapors remaining uncondensed in the reflux tower 9 are being taken off to the condenser 12 to condense to form the distillate product, reflux condensate and admixed raw oil from the reflux tower 9 is being discharged into the separating drum where lighter and lower boiling components are separated by vaporization consequent to circulation of this oil through the heating tubes 27 again to escape to the reflux tower 9 through connection 29, and the remaining reflux condensate and admixed raw oil stripped of such lighter and lower boiling components is returned to the bulk supply drum 1 through the heating tubes 8. The heating gases from the fire-box 105 of the furnace 3 pass first over the heating tubes 8, then over the heating tubes 2 and finally over the heating tubes 27. The reflux condensate from the reflux tower 9 is thus subjected to the most se- 110 115 120 125 130

vere conditions prevailing in the furnace 3 but only after separation of lighter and lower boiling components. The heating tubes 2 through which oil containing 5 tarry or pitchy components produced in the cracking operation is circulated are at the same time protected by the heat absorbed from the heating gases by the more refractory and cleaner oil circulating through the 10 heating tubes 8. The operation is so continued until the still is to be shut down in the regular course of operation or until shortly before this time.

The separation of lighter and lower boiling 15 components from the reflux condensate or oil mixture from the reflux tower 9 in the separating drum 24 may be promoted by reducing the pressure on this oil or oil mixture as it is discharged through connection 23. 20 for example by means of valve 37. In such operation, connection 29 instead of being arranged to discharge into the reflux tower 9 is connected to a separate condensing system. Such a separate condensing system is illustrated 25 in Fig. 2 and is described in connection with the discussion of that figure. A separate condensing system may also be employed in conjunction with the specific apparatus illustrated in Fig. 1 if the branch vapor line 29a is connected to the vapor line 29 as illustrated. 30 Similarly, the vaporization of lighter and lower boiling components from the reflux condensate or oil mixture from the reflux tower 9 may be effected entirely by reducing the pressure on this oil or oil mixture 35 in many cases. The apparatus illustrated in Fig. 2 is adapted for carrying out the invention in this way.

Referring to Fig. 2, the apparatus illustrated 40 is in many respects similar to that illustrated in Fig. 1, and to avoid duplicity of description the same or corresponding parts have been designated by the same reference character with the letter *a* appended. The 45 apparatus illustrated in Fig. 2 differs from that illustrated in Fig. 1 in that means for heating oil in the separating drum 24a are not provided and instead means are provided for maintaining this drum under a pressure 50 lower than that prevailing in the reflux tower 9a, pressure regulating and reducing valve 37a being provided in connection 23a for this purpose. Also, the vapors from the 55 separating drum 24a are discharged through connection 29a to a separate condenser 38 and receiver 39. The operation of the apparatus illustrated in Fig. 2 is likewise in general similar to the operation of the apparatus illustrated in Fig. 1.

In carrying out the invention in the apparatus illustrated in Fig. 2, the pressure 60 on the reflux condensate or oil mixture discharged from the lower end of reflux tower 9a through connection 23a is reduced as it 65 passes valve 37a, lighter and lower boiling

components of the reflux condensate or oil mixture being vaporized as a consequence of this reduction in pressure and being separated from the reflux condensate or oil mixture remaining unvaporized in the separating drum 24a to escape through connection 29a. This pressure drop may amount, for example, to something in the neighborhood of 5-20 pounds per square inch. The pressure in the separating drum 24a may be 70 maintained and regulated by means of valve 40 or by means of suitable valves arranged beyond the condenser 38 or the receiver 39. A reflux tower may also be interposed in the vapor connection between the separating drum 24a and the condenser 38 with connections arranged to return reflux condensate to the separating drum. The refluxing therein may be effected by indirect heat exchange 80 with a suitable cooling medium or by the introduction of a part of the raw oil supplied to the operation or by the introduction of a part of the distillate product. If several stocks are to be supplied to the operation some of which are more refractory than others, such refractory stocks may with advantage be supplied to the operation by direct introduction into such a reflux tower. The reflux condensate or oil mixture stripped 85 of lighter and lower boiling components separated as vapors in separating drum 24a is then forced through the heating tubes 8a by means of pump 30a and then into the bulk supply drum 1a through connection 32a and the circulating connections 6a. 90

In one aspect, it will be apparent that the invention provides an improved method of operation in which reflux condensate separated from the vapors produced in a primary cracking operation is subjected to more severe cracking conditions in a secondary cracking operation after separation from this reflux condensate of lighter and lower boiling components tending to involve over-cracking or excessive formation of "carbon" under such more severe cracking conditions. While the operations more specifically described, including discharge of the hot oil products from such secondary cracking operation into the hot oil products of such primary cracking operation is particularly advantageous, certain advantages of the invention, in this aspect, are secured where the hot oil products from the secondary cracking 105 operation are handled separately. The hot oil products from the secondary cracking operation may, for example, be discharged into a separate vaporizing drum for the separation of vapors from unvaporized components and these vapors may be separately fractionated to recover the desired distillate product. 110

I claim:

1. The improvement in the cracking of 110 hydrocarbon oils, which comprises heating

- a body of oil to a cracking temperature by 5
circulating the oil over heating surfaces externally in contact with heating gases and taking off vapors therefrom under pressure, 70
subjecting these vapors to a refluxing operation and taking off from the refluxing operation vapors including vapors of the desired distillate product, separating components of the reflux condensate suitable as 75
10 components of the desired distillate product by vaporization from the reflux condensate after discharge from the refluxing operation, thereafter passing the reflux condensate stripped of such components over separate 80
15 heating surfaces externally in contact with heating gases, and passing heating gases for supplying heat to the operation first over the last mentioned separate heating surfaces and then over the first mentioned heating surfaces. 85
20 2. An improved method of cracking hydrocarbon oils, which comprises heating a body of oil to a cracking temperature by circulating the oil over heating surfaces externally in contact with heating gases and taking off vapors therefrom under pressure, subjecting these vapors to a refluxing operation and introducing raw oil into direct contact with the vapors in the refluxing operation, taking off from the refluxing operation vapors including vapors of the desired distillate product, separating components of the admixed 90
25 reflux condensate and raw oil suitable as components of the desired distillate product by vaporization from this oil mixture after discharge from the refluxing operation, thereafter circulating the oil mixture stripped of such components over separate heating surfaces externally in contact with heating gases 95
30 and back to the said body of oil, and passing heating gases for supplying heat to the operation first over the last mentioned separate heating surfaces and then over the first mentioned heating surfaces whereby the oil 100
35 circulating over the last mentioned heating surfaces is heated to a higher temperature than the oil circulating over the first mentioned heating surfaces. 105
40 3. The improvement in the cracking of hydrocarbon oils, which comprises heating a body of oil to a cracking temperature by circulating the oil over heating surfaces externally in contact with heating gases and taking off vapors therefrom under pressure, subjecting these vapors to a refluxing operation and introducing raw oil into direct contact with the vapors in the refluxing operation, taking off from the refluxing operation vapors including vapors of the desired distillate product, vaporizing and 110
45 separating components of the reflux condensate suitable as components of the desired distillate product therefrom by reheat- 115
50 ing the reflux condensate after discharge from the refluxing operation to a temperature higher than that at which it is discharged therefrom, thereafter passing the reflux condensate stripped of such components over separate heating surfaces externally in contact with heating gases, and passing heating gases for supplying heat to the operation first over the last mentioned separate heating surfaces and then over the first mentioned heating surfaces whereby the oil circulating over the last mentioned heating surfaces is heated to a higher temperature 120
55
60
65

than the oil circulating over the first mentioned heating surfaces.

6. The improvement in the cracking of hydrocarbon oils, which comprises heating a body of oil to a cracking temperature by circulating the oil over heating surfaces externally in contact with heating gases and taking off vapors therefrom under pressure, subjecting these vapors to a refluxing operation and taking off from the refluxing operation vapors including vapors of the desired distillate product, vaporizing and separating components of the reflux condensate suitable as components of the desired distillate product therefrom by reducing the pressure on the reflux condensate after discharge from the refluxing operation, thereafter passing the reflux condensate stripped of such components over separate heating surfaces externally in contact with heating gases, and passing heating gases for supplying heat to the operation first over the last mentioned separate heating surfaces and then over the first mentioned heating surfaces whereby the oil circulating over the last mentioned heating surfaces is heated to a higher temperature than the oil circulating over the first mentioned heating surfaces.

7. The improvement in the cracking of hydrocarbon oils, which comprises heating a body of oil to a cracking temperature by circulating the oil over heating surfaces externally in contact with heating gases and taking off vapors therefrom under pressure, subjecting these vapors to a refluxing operation and taking off from the refluxing operation vapors including vapors of the desired distillate product, separating components of the reflux condensate suitable as components of the desired distillate product by vaporization from the reflux condensate after discharge from the refluxing operation, and thereafter passing the reflux condensate stripped of such components over separate heating surfaces externally in contact with heating gases of higher temperature than said first mentioned heating gases and thereby heating the oil circulating over the last mentioned heating surfaces to a higher temperature than the oil circulating over the first mentioned heating surfaces.

8. The improvement in the cracking of hydrocarbon oils, which comprises heating a body of oil to a cracking temperature by circulating the oil over heating surfaces externally in contact with heating gases and taking off vapors therefrom under pressure, subjecting these vapors to a refluxing operation and taking off from the refluxing operation vapors including vapors of the desired distillate product, separating components of the reflux condensate suitable as components of the desired distillate product by vaporization of the reflux condensate after discharge from the refluxing operation, thereafter heating

the reflux condensate stripped of such components to a cracking temperature by passing it over separate heating surfaces externally in contact with heating gases, and supplying heat to the first mentioned heating operation by passing heating gases from the furnace first over the last mentioned heating surfaces and then over the first mentioned heating surfaces.

In testimony whereof, I have subscribed my name.

EUGENE C. HERTHEL.
